Application September 19, 1955, Serial No. 534,941

2 Claims. (Cl. 257—262.16)

This invention relates to a fin and tube type heat exchanger and method of making the same.

It is an important object of the present invention to provide an improved method of making a fin and tube type heat exchanger.

It is a further object of the present invention to provide a novel heat exchanger of the fin and tube type having means for retaining the tube with the fins which positively presses the tube into good heat exchange contact with the fins.

It is a further object of the present invention to provide a novel fin and tube type heat exchanger construction which can employ serpentine tubing without any need for jointed return bends.

It is still another important object of the present invention to provide a novel and improved method for making a fin and tube type heat exchanger which affords improved heat transfer between the tube and the heat exchange fins.

In accordance with the features of the present invention, the heat exchange tubing is assembled in a series of notches, and elongated channel members are pressed into the notches to close the same, the channel members being placed under a predetermined tension during the assembly process as they are conformed to the periphery of the tubing to exert a positive pressure on the tubing urging the tubing against the end of the notches. More specifically, the channel members comprise a relatively flat body portion having turned flanges at the longitudinal edges thereof which, as the body portion is conformed to the periphery of the tubing, are snapped into niches in the sides of the notches in such a manner as to retain the channel member in resilient tensioned condition to press the tubing against the ends of the notches.

Other and further important objects and features of the present invention will be apparent from the following disclosure in the specification and the accompanying drawings.

On the drawings:

Figure 1 is a side elevational view of a fin and tube type heat exchanger in accordance with the present invention, the major number of the fins intermediate the ends of the heat exchanger being omitted for simplicity;

Figure 2 is a bottom plan view of the structure of Figure 1;

Figure 3 is a left end elevational view of the structure of Figure 1;

Figure 4 is a view illustrating the manner in which the fins are formed from a flat blank;

Figure 5 is a cross sectional view taken generally along the line V—V of Figure 4;

Figure 6 is a side elevational view of a fin ready to be assembled with the tubing;

Figure 7 is an end elevational view of the structure of Figure 6;

Figure 8 is a fragmentary bottom plan view of the structure of Figure 6;

2

Figure 9 is a side elevational view of a channel member in initial condition prior to assembly with the fin and tube structure to retain the tube with the fins;

Figure 10 is an end elevational view of the structure of Figure 9;

Figure 11 is a diagrammatic view illustrating a tool for pressing the channel member into the respective notches; and

Figure 12 illustrates the manner in which the turned flanges of the channel member are snapped into engagement with niches at the sides of the tube receiving notches.

As shown on the drawings:

As seen in Figures 1, 2 and 3, the tube and fin heat exchanger of the present invention may, by way of example, comprise a pair of serpentine tubes 10 and 11 having respective straight run portions 10a and 11a and respective connecting bend portions 10b and 11b. As seen in Figure 1, the straight run portions have a multiplicity of fin plates 13 extending at generally right angles to the planes of the tube runs 10a and 11a and interconnected with the tubing. Specifically, as seen in Figure 3, the fin plates 13 each have a succession of notches 15 in one longitudinal edge 13a thereof and a series of notches 17 in an opposite longitudinal edge 13b. The notches are spaced along the length of the fin so as to receive the respective tube runs 10a and 11a, the notches 17 preferably being offset longitudinally from the notches 15. A tube length 20 may connect the last tube run of tubing 10 with the first run of tubing 11.

Bracket members 22 and 23 may have elongated slots such as 24 and 25 for receiving the respective return bends 10b and 11b, the brackets 22 and 23 having suitable flange means 22a and 23a for mounting of the heat exchanger.

For locking the tubing in the respective notches and for pressing the tubing into firm heat exchange relation to the fin plates, channel members 30 are provided each of which extends the length of one of the tubing runs 10a or 11a and has turned flanges 30a and 30b extending into niches 32 and 33 formed at the sides of each notch 15 and 17, the free ends of the flanges 30a and 30b engaging shoulder portions 34 and 35 which face the ends of the notches.

It will be understood that the fins are preferably uniformly spaced over the entire length of the tube runs between the brackets 22 and 23, and that the intermediate fins in Figure 1 and Figure 2 have been omitted for simplicity of illustration.

The manner of forming the fins 13 is illustrated in Figures 4 to 8. As illustrated in Figures 4 and 5, the fins may be formed from a flat sheet by stamping slots such as 40 and 41 along the respective longitudinal edges of the sheet, and also forming stiffening embossments such as 42, 43, 44 and 45 uniformly along the blank. The slots 40 and 41 have arcuate end edges such as 45' for conforming to the periphery of the tubing and have lateral recesses such as 46 for providing the niches 32, 33. The projections such as 47 at the mouth of the slot 40 are adapted to be turned down as indicated at 48 in Figure 7 to reinforce the shoulder portions 35, and the end portion 45' is adapted to be turned down to provide an arcuate end wall portion 51 for increasing the heat exchange contact between the fin plate and tubing.

Figures 9 and 10 illustrate the initial condition of the channel members wherein they comprise a flat planar body portion 55 with turned flanges 30a and 30b formed on sharp right angle corners relative to the body portion. The channel members or tube retainers may for example be .0040 inch thick spring red brass, and the body portion 55 may have an outside span of about .360". The

flanges may have an outside length of about .125" and the length of the channel member may be about 20". The tubing may have a diameter of about $\frac{3}{8}$ " and the spacing between the flanges 48 at the mouth of the notches may be about .40" while the spacing between the walls of the niches at the opposite sides of the notches may be .43". The depth of the notches may be about .37" plus $\frac{1}{2}$ the diameter of the tubing. The length of the flanges 48 in a direction transverse to the length of the fin plates may be about .11" while the length of the niches 46 may be about .26".

In assembling the retaining strips with the tube and fin structure after the tubes have been inserted in the respective notches, the strips may be mounted on die projections such as indicated at 60 having elongated recesses 61 of contour to conform to the external periphery of the tubing and with sharp edges. As illustrated in Figure 12, as the projections 60 are moved into the notches, the planar portion 55 of the channel member is flexed transversely into conforming contact with a portion of the periphery of the tubing, this flexing urging the flange portions 30a and 30b to deflect out laterally into engagement with the turned edge flanges 48 at the mouth of each notch. It will be observed that the free ends 62 and 63 of the flanges are bent due to engagement with the flanges 48 and cannot assume their normal radial disposition relative to the tubing until the retainer is fully inserted into the notch and in fully conforming relation to the tubing, at which time the free ends 62 and 63 snap into the niches and into engagement with the shoulders 34, 35. The force exerted by the body portion, which tends to resume its normal planar configuration, now urges the free ends generally radially relative to the tubing, forcing them into the corners provided by the niches and preventing the free ends 62 and 63 from becoming dislodged from engagement with the shoulders. Conversely, the body portion of the retainer in tending to resume its planar disposition presses the tubing firmly against the end flanges 51 of the fin plates for good heat exchange contact therewith.

It will thus be appreciated that in final assembled condition, the retainer channels are in resilient tensioned condition between the shoulders 34, 35 and a peripheral portion of the tubing to maintain good heat exchange contact between the tubing and the fin plates. In other words, the shoulders 34, 35 are spaced from the end of the notch in the direction at right angles to the length of the fins a distance less than the diameter of the tubing plus the length of the flanges, to require that the body portion of the retainer be wrapped about the periphery of the tubing and placed under a resilient tension before the flange free ends can engage against the shoulders at the outer ends of the niches.

It will be apparent that many modifications and variations may be effected without departing from the scope of the novel concepts of the present invention.

We claim as our invention:

1. A plate and tube assembly comprising a length of tubing, a plurality of plates stacked in closely spaced overlying parallel relation with an exterior edge of each plate lying flush with corresponding exterior edges of the other plates and with a notch formed in each of said exterior edges in alignment with corresponding notches in the other plates, said length of tubing extending through the aligned notches of the respective plates, the margin of each notch being of U-shape and being defined by interior edge portions of said plate integral with the plate, the interior edge portion of said plate at the inner closed end of each notch contacting a semi-peripheral portion of the tubing, and the interior edge portions at the respective sides of each notch having niches therein extending outwardly from the notch in the direction away from the center line of the notch to provide generally right angle shoulders of substantial extent in the direction at right

angles to the center line of the notch and facing the inner closed end of the notch, said niches having a substantially greater extent along the sides of the notch than the depth of said shoulders, said shoulders joining with adjacent edge portions of the plate defining the bottoms of the niches to define a corner at the ends of the shoulders remote from the center line of the notch, and a single continuous elongated channel retaining member which normally assumes a U-shape with a substantially planar body portion and right angle flanges extending in the same direction from the opposite sides of the body portion and generally at right angles to the body portion, said channel member extending through the aligned notches and having its body portion transversely arced in conforming contact to a further portion of the periphery of the tubing at the side of the tubing nearest the open end of the notch, said arced body portion contacting a portion of the periphery of the tubing substantially less than a semi-periphery thereof and the integral flange portions extending outwardly away from said tubing and forming acute angles of substantially less than 90° with the center line of the notch and extending toward the open end of the notch and laterally away from the center line of the notch and terminating in free ends seated in the corners between the shoulders and the adjacent edge portions of the niches, the transverse extent of the shoulders inwardly toward the center line of the notch from the corners preventing the body portion from assuming its normal planar configuration.

2. A plate and tube assembly comprising a length of tubing, a plurality of stacked plates having aligned notches therein, said length of tubing extending through the aligned notches of the respective plates, the margin of each notch being of generally U-shape and being defined by interior edge portions of the plate, the interior edge portions of the plate at the inner closed end of each notch contacting the periphery of the tubing and leaving a portion of the periphery of the tubing nearest the open end of the notch uncontacted thereby, and the interior edge portions at the respective sides of each notch providing shoulders spaced from said inner closed end of said notch, and a single continuous elongated channel retaining member of generally U configuration in cross-section extending through the aligned notches and including a transversely arced body portion of transverse arcuate extent substantially equal to the transverse diametric extent of said tubing, said arced body portion being in conforming contacting relation to the portion of the periphery of the tubing nearest the open end of the notch, said body portion having an arcuate transverse extent substantially less than a semi-periphery of the tubing and having integral flange portions extending outwardly away from said tubing and at an acute angle to the center line of the notch substantially less than a right angle, said flange portions extending toward the open end of the notch and laterally away from the center line of the notch and terminating in free ends seated against the shoulders at the respective sides of each notch to hold the retaining member in each notch with the arced body portion thereof in contacting relation to the tubing.
